(57) **CLAIM**

The ornamental design for a passenger automobile, as shown and described.

DESCRIPTION

FIG. 1 is a front perspective view of a passenger automobile showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a front perspective view of a passenger automobile showing our second embodiment of our new design;

FIG. 8 is a front view of the passenger automobile of FIG. 7;

FIG. 9 is a rear view of the passenger automobile of FIG. 7;

FIG. 10 is a left side view of the passenger automobile of FIG. 7;

FIG. 11 is a right side view of the passenger automobile of FIG. 7; and,

FIG. 12 is a top view of the passenger automobile of FIG. 7. The bottom surface of the passenger automobile is unornamented.

The portions indicated in broken lines are for illustrative purposes only and form no part of the claimed design.
